United States Patent [19]

Mueller et al.

[11] Patent Number: Des. 308,070

[45] Date of Patent: ** May 22, 1990

[54] RIBBON CASSETTE

[75] Inventors: **Hans W. Mueller, Kenneth D. Vought**, both of Cortland, N.Y.
[73] Assignee: **Smith Corona Corporation, N.Y.**
[**] Term: **14 Years**
[21] Appl. No.: **127,002**
[22] Filed: **Nov. 30, 1987**
[52] U.S. Cl. **D18/12**
[58] Field of Search **D18/12, 22, 23, 99; 400/196, 196.1, 208**

[57]

CLAIM

The ornamental design for a ribbon cassette, as shown.

DESCRIPTION

FIG. 1 is a perspective view taken from the top, rear, and left side of a ribbon cassette showing my new design;
FIG. 2 is a right side elevational view thereof;
FIG. 3 is a rear elevational view thereof;
FIG. 4 is a left side elevational view thereof;
FIG. 5 is a top plan view thereof;
FIG. 6 is a front elevational view thereof; and
FIG. 7 is a bottom plan view thereof.

FIG. 5

FIG. 6

FIG. 7
